UNITED STATES PATENT OFFICE.

MELVILLE E. DAYTON, OF CHICAGO, ILLINOIS.

CAR-WHEEL-TRUING MACHINE.

SPECIFICATION forming part of Letters Patent No. 334,647, dated January 19, 1886.

Application filed April 16, 1885. Serial No. 162,518. (No model.)

To all whom it may concern:

Be it known that I, MELVILLE E. DAYTON, of Chicago, in the county of Cook and State of Illinois, have invented certain new and useful Improvements in Car-Wheel-Truing Machines; and I do hereby declare that the following is a full, clear, and exact description thereof, reference being had to the accompanying drawings, and to the letters of reference marked thereon, which form a part of this specification.

This invention relates to lathes of that class which are adapted to turn or otherwise true the rims of car-wheels when secured upon their axles, certain features of the invention being more especially intended to meet the requirements of the case in which the journals on the axle are exterior to the wheels.

The general objects and nature of my improvements will appear from the following description and the appended claims.

It is among the objects of the construction herein set forth that the machine shall have sufficient driving force and steadiness of operation to carry both of the wheels at the same time against turning-tools, and, if need be, each wheel against two such tools simultaneously, and to insure proper accuracy in the heavy work thus to be done.

For this purpose the invention contemplates a construction of the chuck whereby the latter of itself more completely sustains the wheel or furnishes the fulcrum for its rotation against the tool in which the "center" cuts little or no figure as a fulcrum, and in which the strength of the axle is utilized only or principally to hold the wheel in engagement with the chuck. To this end the chuck is contrived to stand or to present its driving-points proximate to the wheel, notwithstanding the journal is outside the wheel, and is provided with means for engaging the wheel (or for engaging the wheel and the axle adjacent thereto) in such manner and at such points that practically no lateral strain falls upon the end center, if the latter be employed. In furtherance of this end also, and as preferably constructed, the chuck is shown as provided at its driving-points with radially-movable jaws, operating

as drivers, which bear outwardly against the under face of the wheel-rim, and which thus not only "drive" but uphold the wheel in all directions against the tool.

To facilitate the insertion of the wheels and their "outside" journaled axle in the machine without extensively retracting or separating the chucks to admit the protruding ends of the axle, a space is provided between the driving-points of the chucks through which said ends of the axle may enter laterally to their proper positions central to the chucks. Two forms of construction are shown with reference to this end. One consists of a deep chuck having a series of radially-movable driving-jaws or "drivers," applied at about equidistant points on the vertical face of the chuck, and a radial groove between two of said points to admit the end of the axle. The places or points on the chuck at which these drivers stand are herein termed the "driving-points," or the "fixed driving-points," of the chuck. The other consists in a chuck constituted of a face-plate having rigid posts projecting into proximity to the wheel, which posts are essentially integral with the plate, though shown and preferably made movable thereon. To these posts are applied the drivers, and between them space is afforded for the lateral introduction of the protruding ends of the axle. The outer ends of the posts referred to constitute the fixed driving-points of this form of chuck. In either of these equivalent constructions no extended movement of either chuck-head is required, and the operation of introducing the wheels and their axle is, therefore, a short and simple one.

The form of chuck, consisting of a face-plate having rigid posts for the support of drivers, and having said posts movable, serves the object of adapting the machine to work upon wheels of widely-varying diameters. The use of such posts also enables the invention to be applied to machines already constructed of the older form.

It is a further feature of the machine, as herein set forth, that while particularly adapted to centering and holding wheels mounted upon axles having outside journals, it is ready

ly adjustable to wheels having inside journals, without relative movement of the opposing chucks for this purpose.

In the accompanying drawings, which illustrate one form of machine embodying my invention, Figure 1 is a plan view of the lathe, with a pair of car-wheels centered and set in place therein, ready for turning. Fig. 2 is a longitudinal vertical section of the machine-bed, taken in the plane of the axes of the chucks, and showing the said chucks and other principal parts of the lathe in elevation, looking from front to rear of the machine. Fig. 3 represents the driving-gear of the lathe in end elevation, the end of the bed piece or frame being removed and the tool-rests being absent. Fig. 4 is a face view of a chuck containing a radial recess by which the projecting journaled end of the axle is admitted to its central position relative to said chuck, and also showing one form of the centering device, consisting of two "universal" chuck-jaws having angular recessed ends to receive and center the axle by external lateral engagement therewith. Fig. 5 is a vertical axial section of a chuck constructed as shown in Fig. 4, the section being taken in the line $x-x$ of said Fig. 4, and showing a car wheel and axle in place and held by the chuck, said wheel being also shown in vertical axial section. Fig. 6 is an axial section of the chuck shown in Fig. 4, taken on the line $y-y$, an "outside" journaled axle of the wheel being shown by dotted lines. Fig. 7 corresponds with Fig. 6, except that it shows an "end" centering device which may be used alternatively with the centering-jaws, as also shown in said figure, or which may be used conjunctively with said centering-jaws, either upon axles having exterior journals or those having interior journals, the said figure showing an axle having its journals between the wheels, or without external projections, as in the case of locomotive truck-wheels. Fig. 8 shows the same mechanism as Fig. 7, but applied to an axle having outside journals. Fig. 9 shows in front elevation a chuck consisting of a face-plate having radially-movable posts thereon and sliding holding and driving jaws mounted in the outer ends of said posts. There are also shown in this figure projected center-jaws similar to those shown in previous figures for externally and laterally grasping the protruding end of the axle but independently actuated. Fig. 10 is a vertical axial fragmentary section of the matters shown in Fig. 9, together with a fragment of a wheel centered and set in place. Fig. 11 is a central section of one of the posts of Fig. 10 detached. Fig. 11^a is a fragmentary front view of the driving-jaw of Fig. 11, showing the form of the stud. Fig. 12 is an alternative construction of one of the driver-jaws as to one of its details. Fig. 13 is a central section of one of the posts, showing 65 a driving-jaw fitted to slide in a head, which is provided with a shank having a movement

in the post in a direction at right angles to the face-plate. Fig. 14 is a transverse section of the slide F^a of Fig. 13 through the flattened part thereof. Fig. 15 is a transverse section of the machine-bed in front of one of the chucks, showing one of the two adjustable tracks which carry the wheels into a position in the machine in which the protruding ends of the axle may be engaged by the hoisting devices on the chucks, and thereby lifted to the centers.

A is any suitable form of bed or frame, upon which are placed the two stocks or the head and tail stocks B and B', and the tool-rests. In the stocks B and B' are rotatably mounted the spindles C C, which carry the spindle-heads or chuck-heads C', to which the chucking devices are rigidly attached. The two spindle-heads are both, as herein shown, provided with peripheral cogs c, which mesh with the pinions d and d' on the heavy drive-shaft D, located, preferably, below the upper surface of the bed-plate and running longitudinally of the machine, as shown in Figs. 2 and 3. By this means both chucks are driven in unison from a common source of power. The shaft D is illustrated as being driven by a suitable train of gearing from a cone belt pulley, D'. This, however, is only one of numerous forms of driving mechanism that may be employed, and I am not restricted to any particular devices for this purpose.

One of the stocks, B', is made longitudinally movable upon the machine-bed, to admit the wheels over the short projections on the chuck-jaws (which are herein shown as proper devices by which to engage the car-wheels with the chucks) and to afford adjustment of the machine to wheels mounted at different distances apart on their axles. Accordingly the adjacent pinion d' on the shaft D is shown broad-faced to engage the rack c of the spindle-head C' in these changes of its position. A suitable device for shifting the tail-stock B' for these adjustments is shown in the screw B², engaged with the interiorly-threaded lug B³, which depends from the tail-stock, and provided with the hand-wheel B⁴. If desired, both stocks may be similarly movable on the machine-bed; or, instead of moving either stock itself, the familiar equivalent of a spindle having a longitudinal movement in the stock may obviously be employed for the short adjustment of the chucks to the wheels.

Proceeding now to describe the more distinctively novel features of construction in my improved machine, and referring more particularly here to Figs. 1 to 8, inclusive, it will be seen that each chuck, as shown in said figures, consists, first, of a cylindric body, C, firmly secured to the spindle-head and provided with a radial slot or recess, C', of suitable size to admit the projecting end of the axle freely to the center of the chuck; second, radially-moving centering-jaws E, fitted to slide in the chuck at opposite sides of its cen-

ter, for externally grasping and centering or supporting the said projecting end of the axle when so admitted through the slot C², to a position between them; third, screws E', for operating said jaws, provided with fixed pinions e², gear-wheels E², engaged with said pinions, and also with a circular rack, E³, traveling in an annular groove in the spindle-head C⁴; and, fourth, independently-movable holding and driving jaws F, also fitted to slide in the face of the chuck, for engaging the latter firmly with the car-wheel after the said wheel has been properly centered.

The jaws E, when two in number, are placed one on each side of the radial recess C² at its inner end, so that when they are radially retracted the journaled end of the axle X may be directed into position between them. When relied on for centering the axle, they are also constructed with V-shaped notches in their ends, or with branches e e', which operate in a familiar way when the jaws are closed down upon the axle to bring the latter to a center with the chuck, as indicated. Preferably, the rearmost arms, e', of these jaws are longer than their fellows, so that when the latter are spread only far enough to freely admit the axle the longer arms, e', will strike the axle and the more readily bring the same to place in closing thereon.

The holding and driving jaws F, when three in number, are preferably placed with reference to the radial slot C² and to the central jaws, E, as shown in Fig. 4, or one on each side of and one directly opposite said slot. These holding and driving jaws are desirably formed to project beneath the wheel-rim and also to stand opposite the vertical face of said rim, as clearly shown in Figs. 5 to 8, inclusive, but with the purpose of forcibly engaging the wheel-rim by an outward pressure of the parts f, which engage its inner or under surface. These outwardly-bearing faces of the holding-jaws are therefore shown serrated. This construction and use of said jaws is not new.

To point out certain details of construction in the radially-recessed form of chuck above described, the cylindric body C' thereof is shown in the drawings as hollow, and provided with brackets or an inwardly-directed flange, C⁵, by which the same is bolted to the spindle head C⁴. For the inner support of the pivot pins e² of the pinions E² lugs e are cast on the inner vertical face of the chuck-shell. In Figs. 7 and 8, a centering-bar, C⁵, is fitted to slide in a hollow form of chuck-spindle C, and to run out through the inner end of the radial slot C² of the chuck when required. In this case the said slot C² may extend in depth the full width of said cylinder, as shown in Fig. 8, wherein the opening thereof is visible beyond the axle-journal. But when the centering bar C⁵ is not present, the slot may be inclosed by a web, C⁶, integral with its side walls. These and other mere details of mechanical construction are all variable without departure from my inven-

tion, an operative form of which is sought to be shown. The centering-bar C⁵, carrying a center, c², to enter the original center countersink of the axle, as shown in Figs. 7 and 8, is generally desirable whether the jaws E be present or not, and will commonly be employed. This center bar, C⁵, is splined in the chuck-spindle C, as shown at c³, and rotates therewith, and is operated by a hand-wheel screw, C⁷, at the outer end of the spindle, as more clearly shown in Figs. 7 and 8. The center bar is preferably fitted to the inner end of the slot C² of the chuck-body, so as to derive support therefrom when run out to engage inside journaled axles, as shown in Fig. 7; and to this end the said inner end of the slot C² will desirably be enlarged, as indicated in Figs. 4 and 8, so that the center bar (made of corresponding size) may not wholly want such support on the side of the slot.

Proceeding next to describe the alternative form of chuck illustrated in Figs. 9 to 11, inclusive, the spindle-head C⁴ of said figures has firmly secured on its vertical face a suitable number of very rigid posts, F', which reach into proximity with the car-wheel. In the outer end faces of these posts driving-jaws F are fitted to slide radially of the head or plate C⁴, as in the chucking mechanism previously described. Central radially-sliding jaws E may also be applied to the spindle head or plate C⁴, as seen in Figs. 9 and 10. In the drawings these jaws are also mounted to slide in the outer ends of posts E⁴, so as to engage the axle near the wheel, and are operated by screws E', not connected but independent. The posts E⁴ are preferably erected upon opposite ends of a plate, E⁵, and cast or formed integral therewith. Said plate E⁵, as shown, has a central boss, e⁵, on its back, which sets in a corresponding recess in the plate C⁴ for greater certainty of position and stability, and is further held in place by bolts e⁴. If a center bar, C⁵, is employed, the plate E⁵ has a suitable central aperture therefor. In this construction of the chuck the posts F', and, consequently, the driving-points of the chuck, which are the outer ends of these posts, are separated by spaces between them, through some one or other of which the projecting end of the axle may be admitted laterally to its central position, substantially as it is admitted through the slot or groove C² of the form of chuck previously described, and without retraction or advancement of the chuck itself beyond what may be necessary to clear the driving-jaws from or to engage them with the wheels.

In addition to the movement of the driving-jaws F in their guiding grooves, (illustrated in all figures of the drawings,) Figs. 9 and 10 illustrate the posts or parts F', in which said jaws are mounted, as themselves movable radially on the head or plate which supports them. For this purpose I prefer to construct the posts with broad-faced base plates or flanges

F^2 , provided with slots f' for the holding-bolts f^2 . To afford a still more extended radial adjustment of the posts F' , I also prefer to employ for each post two parallel T-grooves in the plate C^4 , in which the heads of the holding-bolts f^2 may be seated. By this means the posts may be set in position for any size of wheel for which the plate may be adapted and there secured as firmly and rigidly as though made integral with the plate itself.

In Figs. 11, 11^a, and 12 are shown two slightly-different forms of adjunctive devices for giving a lateral bearing of the driving-jaws upon the car-wheel rim, consisting of a stud, f^3 , placed in a hole in the jaw exterior to the projection f , and adapted to be run out into contact with the edge of the wheel-rim.

In the construction of Figs. 11 and 11^a the stud is flattened at its sides, so as not to rotate in its correspondingly-shaped seat, and is screw-threaded on its partly-cylindric surfaces to receive the nut f^4 , which occupies a slot in the top of the jaw. By rotating the nut the stud may be run in or out in a familiar manner so as to bear properly against the side of the wheel-rim, and thereby still more perfectly steady the wheel under the action of the turning-tool.

In Fig. 12 the stud f^3 is tapped directly into the jaw F , and has an external square by which it may be turned as required.

In operating the machine described it is desirable to avoid lifting and handling the car-wheels and their axle as far as possible. I therefore propose, generally, that the machine be set in a pit to about the depth of the frame A, (which may be shallower than shown,) in order that the wheels may be run in upon the bed upon practically horizontal tracks. The tracks should be adjusted to carry the axle to a position a little below that which it will occupy when centered and set in the machine, and in this case the chucks will be rotated into position to admit the axle ends into the slots or spaces between their driving points as the wheels are rolled in upon their tracks. Any ordinary or suitable jacking devices may be used to lift the wheels and to raise the axle to approximately the desired position to be finally centered before running up the tail-stock and shoving the wheels over the driving-jaws F. It is contemplated, however, that the jaws E will be used to first lift the axle, and when this is done, and before closing said jaws tightly upon the axle or accurately bringing the axle to its center, to run up the tail-stock, for the purpose of pushing the axle endwise and carrying the wheels over the driving-jaws F. This done, the axle may be finally and accurately brought to center either by the jaws E or by the center-bars, C⁵, according to which may be used for the purpose, or by co-operation of both, if both are present. I prefer to rely on the centering-bar and its point c^2 for finally centering the axle by its countersinks, and to use the jaws E to first bring the axle very nearly to center, so

that the center points will enter the countersinks, as above described, and, finally, after the center points are set up, to then close the jaws E down tightly upon the axle, in order to hold the same more firmly and to prevent its springing while the driving-jaws are being set, as well as to aid in supporting the wheels when, subsequently, the wheels are being turned. The jaws E may obviously be constructed to bear upon the journals, or upon the larger part of the axle nearer the wheels, as may be desired, and if used only to jack up the axle only the lowermost of said jaws need be present or used.

In Fig. 15 one of two similarly-adjustable tracks for guiding the wheels and axle proximately to place is shown. The sections T' of the tracks are hinged at their outer ends by a suitable joint, and their inner ends, which extend over the machine-bed, are vertically adjustable, so as to direct the axle to a position with its centers slightly below the centers of the lathe, but with the journals or protruding ends between the jaws E, (or over the single or lower jaw E, if only one on each chuck is present, as shown in Fig. 15, for the sole purpose of lifting the axle to place.) In the use of the radially-slotted form of chuck the axles may, if desired, be guided by the tracks into the outer ends of the slots C², and the chucks being held the axle may be rolled upon its journals inwardly along said slots to finally rest upon the lower and lifting jaws, E. Manifestly the vertically-adjustable tracks may be made to raise the wheels and axle into position to receive the centering devices.

In order to obviate the necessity of all movement of the head or tail stock (after once being adjusted to a given length of axle) for the purpose of bringing the driving-jaws F beneath the rims of the car-wheels, said driving-jaws may be themselves mounted so as to move in a direction at right angles to the face of the chuck, as, for illustration, shown in Fig. 13. In this figure the post F' is made, say, seven or eight inches in external diameter, and is bored to receive the slide F³, which is, say, five inches in diameter. This slide carries the grooved head F⁴, in which the driving-jaw F is held, and is desirably feathered in its seat in the post, so as to not rotate. On its outer side said slide F³ is shown flattened, to give a bearing-surface for a gib or for a set-screw, f⁵, by which the slide is held in a given position. In the absence of familiar devices that may be employed for running the slide F³ out and in, so as to cause the driving-jaws to engage or clear the car-wheel rim, the said slide may be conveniently moved by hand, or by aid of any suitable lever which may be kept at hand for the purpose. This construction will perhaps be preferable to that requiring movement of the tail-stock, inasmuch as it involves no shifting of the car-wheels and their axle endwise of the latter, which may therefore be guided by suitable tracks exactly to the position from

which it will need only to be raised to bring it between the chuck-centers, and because, further, the individual jaws, while loose from the wheels and freed in their bearings, may 5 be quickly managed by the operator without the aid of a helper.

15 A lathe-chuck constructed with a set of independent jaws, and also with a set of connected or universal jaws, is not of my invention. The form of driving-jaws adapted to engage the wheel by the inner or under surface of the wheel is also not new with me, the said form of jaw having been heretofore employed in driving a single wheel detached from its axle.

I am also not the inventor of the duplex tool-slides carrying tools which work on the tread and flange of the same wheel, nor of a hollow spindle provided with a face-plate, and 20 having a follower therein which carries a "center" to engage the countersink of the axle.

A passage next the head C⁴, clear through the cylindric part C¹, and in line with the slot 25 C², may be provided, as indicated by dotted lines of Fig. 8, to admit more light by which to note the position of the axle end with reference to the center c², when the latter is employed.

30 In describing forms of the devices claimed, which possess more than one advantage or function, I desire it to be understood that such modifications as shall attain one or more but less than all said results shall not therefore be regarded as departures from my invention.

I claim as my invention—

1. In a lathe adapted for truing car-wheels when fixed upon their axle, a chuck external 10 to the wheel having driving-points adjacent to the wheel-face, and radially distant from the axle, and provided with a space or passage between its driving-points, adapted to laterally admit the protruding journaled end 45 of the axle to a central position as to the chuck, substantially as described.

2. In a lathe adapted for truing car-wheels when fixed upon an axle having outside journals, the combination, with means for centering the axle, of chucks constructed to present 50 fixed driving-points in proximity to the car-wheels near the peripheries of the latter, said chucks being provided with spaces or passages between their driving points, whereby 55 the protruding ends of the axle may be radially admitted to their central position, and also provided with drivers movably applied to the said driving-points of the chucks for engaging the latter with the car-wheels, substantially as described.

60 3. In a lathe for truing car-wheels when on their axle, the combination, with a chuck, of a movable part adapted to lift the end of the axle to a central or proximately central position with respect to the chuck.

65 4. In a lathe for truing car-wheels when on

their axle, the combination, with an external chuck, of a radially-movable part arranged to engage the adjacent protruding portion of the axle, and adapted to lift it to a central or 70 proximately central position with respect to the chuck.

5. In a lathe for truing car-wheels when fixed upon their axle, the combination, with an 75 external chuck, of a centering-bar, and a radially-movable part which engages the protruding portion of the axle, substantially as and for either or all of the purposes set forth.

6. In a lathe for truing car-wheels when fixed upon their axle, the combination, with 80 the body of an external chuck, of drivers which engage the wheel radially external to the axle, and opposing jaws which laterally engage the protruding portion of the axle, substantially as and for either or all the purposes set forth.

7. The combination, with a lathe adapted for truing car-wheels when fixed upon their 85 axles, and provided with chucks having mechanisms adapted to lift the axle to its central position, of tracks or guides arranged to direct the axles into position to be engaged by said lifting devices, substantially as described.

8. The combination, with a lathe adapted for truing car-wheels upon their axle, and provided with centering devices, of vertically-adjustable tracks for the car-wheels, whereby the latter may be brought into position for the engagement of their axle with the centering 95 devices, substantially as described.

9. In a lathe adapted for truing car-wheels when fixed upon their axle having outside journals, the combination, with a plate on the spindle, of rigid posts projecting from said plate into proximity with the wheel-face near 105 its rim, radially-movable driving-jaws at the free ends of said posts, adapted to engage the wheel-rim, and suitable devices for centering the axle, substantially as described.

10. The combination, with a plate on the 110 spindle of a lathe, of radially-moving driving-posts, suitable devices for securing the posts in a desired position on the plate, radially-movable jaws, as F, mounted on the free ends of said posts, and centering devices, substantially as described, and for the purposes set forth.

11. The combination, with the body of a lathe-chuck, of drivers which are severally movable both radially thereto and at right 120 angles to the plane thereof, substantially as described.

12. The combination, in a lathe chuck, of adjustable slides, as F³, provided with radial guides in their outer faces, driving-jaws mounted movably in said guides, and centering mechanism, substantially as described.

13. In a lathe adapted for truing car-wheels when fixed upon an axle having outside journals, the combination, with a chuck constructed to radially admit the protruding ends of 130 the axle to their central positions, and pro-

vided with driving mechanisms contrived to engage the wheels at points radially distant from the axle, of centering-bars having a range of movement by which they may engage the ends of axles having either outside or inside journals, and means for supporting the axle-engaging ends of the centering-bars when run out into engagement with inside-journalized axles, whereby the same machine is

equally adapted to either class of axles, substantially as described.

In testimony that I claim the foregoing as my invention I affix my signature in presence of two witnesses.

MELVILLE E. DAYTON.
